UNITED STATES PATENT OFFICE.

GEORGE M. BROX AND HOWARD S. KNIGHT, OF MILFORD, NEBRASKA.

RAILROAD-SPIKE.

1,077,970.

Specification of Letters Patent. Patented Nov. 11, 1913.

Application filed March 11, 1912. Serial No. 632,381.

To all whom it may concern:

Be it known that we, GEORGE M. BROX and HOWARD S. KNIGHT, citizens of the United States, residing at Milford, in the county of Seward and State of Nebraska, have invented new and useful Improvements in Railroad-Spikes, of which the following is a specification.

Our present invention pertains to rail-
road spikes—*i. e.*, spikes designed more par-
ticularly for fastening railway rails to sleep-
ers or ties of wood.

The object of our invention is to improve the type of spike embodying means for preventing displacement of the spike after the same is driven home in a sleeper or tie; and the novelty, utility and practical advantages of our said invention will be fully understood from the following description and claim when the same are read in connection with the drawings, accompanying and forming part of this specification, in which:

Figure 1 is a perspective showing our novel spike with the anchoring nail properly positioned therein. Fig. 2 is a view, partly in elevation and partly in section, of the same. Fig. 3 is an elevation of the nail *per se*.

Similar numerals of reference designate corresponding parts in all of the views of the drawings.

Our improved spike comprises a shank 1 and a head 2 which may be and preferably are of the conventional configuration, 35 though they may be of any other configuration compatible with the purpose of our invention without involving departure from the scope of the same as claimed.

In accordance with our invention a vertically disposed hole 3 is formed in the head 2 at a point adjacent one side thereof. In the adjacent side of the shank 1 a vertical groove 4 is formed which registers with the said hole and extends downward from the same about the proportional length or distance illustrated. At its lower end the said groove 4 merges into one end of a bore or passage 5 which extends transversely through the shank from the grooved side to the opposite side thereof. The said transverse bore or passage runs through the spike at a slight downward angle, Fig. 2, for a purpose hereinafter set forth.

In using the spike described the same is driven home in a sleeper or tie of wood. With this done a nail 6 is driven down

through the hole 3 of the spike until the nail head 7 brings up against the upper side of the spike head 2. When the nail is thus driven it will be guided by the hole 3 and the groove 4 to that end of the transverse bore or passage 5 in registration with the groove 4, and hence the lower portion of the nail will be caused to pass through the bore or passage 5 and to project from the side of the spike opposite to that in which the groove 4 is formed. It will also be observed that by reason of the bore or passage 5 being formed through the spike at a slight downward angle—*i. e.*, so that the end of said bore or passage from which the end portion of the nail protrudes will be lower than the end where the nail enters, the said protruding end portion of the nail will be directed outward and upward from the shank. In consequence of this the said lower end of the nail will securely anchor the spike in the sleeper or tie and will effectually prevent the casual loosening or working upward of the spike.

By virtue of the hole 3 being provided in the spike head it will be manifest that when a nail or rather the nail described is driven as stated the nail will be confined in the groove 4; the said groove 4 being preferable to a bore of corresponding length in the spike shank because it can be easily and cheaply formed and also because its formation does not entail material weakening of the shank. From this it follows that because of the employment of the groove, as distinguished from a bore, the spike is not materially weakened between the hole 3 and the bore or passage 5 and yet because of the registration of the groove with the hole 3, the said groove can be depended on to guide the lower end of the nail into the transverse bore or passage 5 with the result that the nail will be bent and caused to form the anchoring barb before referred to.

It will also be observed that by reason of the groove 4 being arranged in registration with the aperture 3 in the spike head, a nail can be expeditiously and easily guided with accuracy into the groove. Moreover the 105 outer wall of the aperture 3 serves to assist the tie into which the spike is driven in retaining the nail in the groove so as to assure the nail following the groove until the nail reaches the receiving end of the bore or pas- 110 sage 5.

Having described our invention, what we

claim and desire to secure by Letters Patent, is:

As a new article of manufacture, a spike comprising a shank and a head integral with 5 and extending laterally beyond one side of the shank; the shank having a transverse bore at an intermediate point in its length and also having a vertical groove in its said side, of even depth throughout its length, 10 extending from one end of the bore to the under side of the extended portion of the

head, and the head having a vertically disposed bore in its extended portion, entirely surrounded by the metal of said portion and alined and communicating directly with the 15 vertical groove of the shank.

GEORGE M. BROX.
HOWARD S. KNIGHT.
